UNITED STATES PATENT OFFICE.

CHRISTOPHER RICHARDSON, OF NEWARK, NEW JERSEY.

DESIGN FOR A CARVING-FORK.

SPECIFICATION forming part of Design No. 28,446, dated April 5, 1898.

Application filed October 6, 1897. Serial No. 654,302. Term of patent 14 years.

To all whom it may concern:

Be it known that I, CHRISTOPHER RICHARDSON, a citizen of the United States, residing at Newark, county of Essex, State of New Jersey, have invented a certain new and original Design for a Carving-Fork, fully described and represented in the following specification and the accompanying drawings, forming a part of the same.

10 My invention relates to a design for a carving-fork having flattened tines.

In the drawings illustrating this design, Figure 1 is a view of the carving-fork, showing the upper side of the tines; and Fig. 2 is 15 an edge view of the tines with a part of the shank of the fork.

In my design the tines are of flattened tapering form, as appears in the top and edge

views exhibited in the drawings, and each tine is formed with a group of transverse 20 crimps or corrugations intermediate to the point and base of the tine.

The leading feature of my design for a carving-fork is the form of the tines having each the group of crimps or corrugations intermediate to the point and base of the same. 25

What I claim is—

The design for a carving-fork, as herein described and shown.

In testimony whereof I have hereunto set 30 my hand in the presence of two subscribing witnesses.

CHRISTOPHER RICHARDSON.

Witnesses:

L. LEE,
THOMAS S. CRANE.
